nerwerk Siemensstadt, near Berlin, Germany

Application June 13, 1935, Serial No. 26,340
In Germany June 21, 1934

11 Claims. (Cl. 179—18)

The present invention relates to a circuit arrangement for characterizing different traffic directions in long distance communication systems, especially telephone systems. In such systems it 5 may happen that the seizing of the connecting line on the part of the preliminary numerical impulse receiver, for example a group selector, takes up so much time, on account of the different switching operations which must take place after 10 the setting impulse train has been taken up, that the subsequent setting impulse train arrives before these switching operations are completed. In this way impulses may be suppressed and false calls are caused. This danger is present especially 15 when additional impulses have to be transmitted as criteria for the selection of the different traffic directions.

The present invention solves the problem of decreasing the time taken up by the characterizing 20 of different traffic directions over a connecting line to the shortest duration possible. This is brought about by the arrangement in which depending upon the desired traffic direction, switching means becomes operative at the outgoing end 25 of the connecting line which effect the characterizing of one traffic direction by the seizing impulse itself, and the characterizing of further traffic directions by the interruption of this seizing impulse.

30 The arrangement according to the invention is applied with advantage in systems in which direct current impulses are transmitted over an inductive path.

The attached figure illustrates an embodiment 35 of the invention. Only those details necessary for understanding the invention are shown.

The connecting line VL, which is electrically isolated by the repeaters Ue1 and Ue2 at the outgoing and incoming ends respectively, can be 40 seized according to one of two traffic directions over the leads a, b, c, or a, b, c1 by a preliminary selector. This is achieved in the known way by setting the selector on different levels. At the incoming end the traffic direction reachable over 45 leads a1, b1, c1 corresponds to seizing the connecting line VL at the outgoing end over leads a, b, and c, and at the incoming end of the connecting line the traffic direction reachable over leads a2, b2, c2 corresponds to seizing over leads 50 a, b, c1 on the part of the preliminary selector.

On seizing the connecting line over the leads a, b, c to which seizure, as already mentioned, the traffic direction at the other end of the line reachable over leads a1, b1, c1 corresponds to the direct- 55 ed traffic direction, the seizing relay C energizes

at the incoming end of the line, in the following circuit: earth in the preliminary selector, wiper c of the selector (not shown), test lead c, contact 1x, windings of relay C, battery, earth. Relay C closes its contacts 2c, 21c, 15c and 19c. By the 5 closing of contact 21c the slow acting relay E is energized. By the closing of contact 19c relay V is energized in the following circuit: earth, contact 27d, winding I of relay V, contacts 26e, 19c, battery, earth. Relay V is short circuited through 10 contact 26v. It thus holds up as a slow acting relay, after the energizing of relay E which as contact 26e breaks the circuit for winding I of relay V, until relay A is energized. On the energizing of relay C the following circuit is completed 15 through winding I of transformer Tr: earth, contacts 3e, 2c, winding I of transformer Tr, battery, earth. This circuit is again broken on the energizing of relay E. Since the contacts of relay E are so adjusted that contact 11e closes before contact 3e opens, and moreover relay V is energized, winding II of transformer Tr thus forms a bridge across the windings of repeater Ue1 through contacts 10v and 11e, and impulse is induced in winding II of transformer Tr and hence also in the primary winding of repeater Ue1 on the breaking of the circuit flowing through winding I of the transformer Tr by contact 3e. This impulse is transmitted to the polarized receiving relay P at the incoming end of the line VL over the repeater 30 Ue1, the connecting line VL, and the repeater Ue2. It does not operate this receiving relay P, however, since the direction of the induced current is such that the armature of the relay remains in the rest position. This impulse merely 35 serves to magnetize the repeater Ue1, which is still magnetized in a particular direction from the preceding call, so that the transmission of the impulses of a new call can take place without disturbance. 40

After relays C and E have energized the following circuit is completed for relay A: earth, contacts 15c, 13e, 12d, winding of relay A, battery, earth. Relay A remains energized until relay D energizes. Relay D is energized over contact 45 22e after the energizing of relay E, but it is constructed as a very slow acting relay so that the resting contact 12d remains closed for some time after the energizing of relay E. Thereupon the following circuit is 50 set up over winding I of transformer Tr, after the energizing of relay A: earth, contacts 4y, 5a, winding I of transformer Tr, battery, earth. Through the completion of this circuit another impulse, 55 the seizing impulse, is induced in winding II of

- transformer T_r and thereby also in the primary winding of repeater U_{e1} . It may be mentioned that relay V is held energized after the energizing of relay A , in the following circuit: earth, 5 contact $24a$, winding II of relay V , resistance W_1 , battery, earth. The impulse induced in the transformer T_r is transmitted to the polarized impulse receiving relay P of the repeater U_{e2} over the connecting line VL .
- 10 The direction of this impulse is such that relay P at the incoming end of the line moves its armature over and thereby sets up the following circuit for relay J : earth, contact $50p$, winding of relay J , battery, earth. Relay J remains energized so long as the armature of the polarized relay P is held in the working position. Relay J completes the following circuit for relay G : earth, contact $63j$, winding of relay G , resistance W_{i2} , battery, earth. Relay G locks up over its 15 contact $56g$ independent of relay J . Relay G completes the following circuit for relay H : earth, contact $54g$, winding of relay H , battery, earth. Relay H closes the following circuit for relay S : earth, contact $60h$, winding of relay S , resistance W_{i4} , battery, earth. Relay S holds up independent of relay H over contact $59s$ until relay J releases.

The seizing impulse is brought to an end at the outgoing end of the line VL by the energizing of the slow acting relay D . Through its contact $12d$ relay D breaks the circuit for relay A . Relay A releases and by opening its contact $5a$ breaks down the circuit through winding I of transformer T_r . The opening of this circuit results in the renewed induction of an impulse in winding II of transformer T_r . This impulse is transmitted to the polarized relay P over the repeater U_{e1} , the connecting line VL and the repeater U_{e2} .

The direction of this impulse is such that relay P of repeater U_{e2} returns its armature to the rest position and opens contact $50p$, but again closes contact $51p$. Relay J is thus deenergized. After relay J has deenergized the short circuit of relay K existing over earth, and contacts $45k$ and $44j$ 40 is broken, and the following circuit is completed for the latter relay: earth, contact $61g$, winding of relay K , resistance W_{i3} , battery, earth. After the energizing of relays G , H and K at the incoming end of the connecting line the connecting device or switch attached to leads $a1$, $b1$, $c1$ is seized, and then relay O energizes over the circuit: earth, contacts $43h$, $42k$, $39g$, winding of relay O , contact $40m$, test lead $c1$ to battery in the attached connecting device. At its contacts $33o$ and $36o$ 45 relay O switches through the leads $a1$ and $b1$. After the release of relay J relay S releases on account of the short circuit over contact $58j$. The repeating of the selecting impulses (setting impulses) in the repeater U_{e2} takes place through relay J by the connection of earth to the $a1$ or $a2$ lead through contact $32j$.

The release of the connection takes place by breaking the test circuit incoming over the c -lead in the selector which is arranged before the line VL . The seizing relay in repeater U_{e1} at the outgoing end of the connecting line VL thereupon deenergizes. Relays E and D then also release. During the time taken by relay D to release, a long releasing impulse is transmitted in the positive direction over the connecting line VL to repeater U_{e2} at the incoming end of the line. The negative impulse is suppressed. These switching processes are not illustrated, as not being essential to the invention. At the incoming end of the connecting line VL the long releasing impulse

causes a prolonged energizing of relays P , J and S . Relay G is short circuited for a prolonged time over contacts $57s$ and $55j$ and thus deenergized. By the release of relay G , relays H and K are also released. After the release of relay G , relay R is energized in the following circuit: earth, contact $62g$, winding of relay R , contact $46s$, battery, earth. In a local circuit relay R energizes a second winding of the polarized relay P and thus causes the return of the armature of P to the rest position; this last circuit is not shown. After this release of the armature of relay P , relay J also releases. Relay J short circuits relay S , relay S deenergizes and all the relays of repeater U_{e2} are once more in the rest position.

If at the incoming end of the connecting line VL the traffic direction reachable over leads $a2$, $b2$, $c2$ is selected the repeater U_{e1} is seized over the testing lead $c1$ by the pre-arranged selector. Relays X and C thereupon energize in the following circuit: earth in the pre-arranged selector, wiper c of the selector, testing lead $c1$, winding of relay X , windings of seizing relay C , battery, earth. Relay C , as already described, effects the successive energization of relays E , V , A and D . 25 After relays C and E have energized an inductive impulse is transmitted over the connecting line VL as also has been described already. This has no effect on the impulse receiving relay P at the incoming end, but merely serves for the corresponding pre-magnetizing of repeater U_{e1} . After relay A has energized a further impulse is transmitted over the connecting line which initiates the seizing. Its direction is opposed to that of the preparing impulse transmitted. An impulse in this direction will be referred to as a positive impulse. After the energizing of relays C and E the following circuit is completed for the slow energizing relay Y : earth, contacts $15c$, $13e$, $16x$, $18z$, winding of relay Y , battery, 30 earth. The energizing of relay Y is delayed to such an extent that it is only energized after relay A , but always before relay D . By opening contact $4y$ relay Y breaks down the circuit through winding I of the transformer T_r . 35 Through the opening of this circuit a fresh impulse is induced in the transformer, this time in the negative direction. This impulse reaches the polarized receiving relay P in repeater U_{e2} over the line VL and causes the opening of contact $50p$ and the closing of contact $51p$. In the repeater U_{e2} relays P and J have up till now been energized through the positive induced impulse of the seizing impulse, but not relays G and H yet, since the negative induced impulse follows immediately. After the closing of contact $51p$ the following circuit is completed in which relay J remains energized, and in addition relay U is energized: earth, contact $51p$, winding I of relay U , contacts $48j$, $47h$, winding of relay J , battery, earth. Relay U energizes and locks up, independent of relay P , over: earth, contact $49u$, winding I of relay U , contacts $48j$, $47h$, winding of relay J , battery, earth. Since relay J remains energized, relay G now also energizes, as already described, 45 in the following circuit: earth, contact $63j$, winding of relay G , resistance W_{i2} , battery, earth. Relay G locks up and energizes relay H . Furthermore, the following circuit is now set up, after the energizing of relay G , for the locking winding II of relay U and for relay M : earth, contacts $52g$, $53u$, winding II of relay U , and parallel to this the winding of relay M , battery, earth. Relay M opens its contacts $34m$, $37m$, and $40m$, and closes its contacts $35m$, $38m$ and $41m$. 50

Thereupon the connection is switched over to the desired traffic direction reachable over leads *a2*, *b2*, *c2*. After the release of relay *J*, relay *K* energizes as already described. The connecting line extending in the desired traffic direction is now seized in the following circuit: earth, contacts *43h*, *42k*, *39g*, winding of relay *O*, contact *41m*, lead *c2*, battery in the subsequent connecting device, earth. In this circuit relay *O* again energizes. 5

10 By closing its two contacts *33o* and *36o*, relay *O* switches through the two speaking leads *a2* and *b2*.

In the repeater *Ue1* relay *Z* energizes in the following circuit after the energizing of relay *Y*: 15 earth, contacts *15c*, *13e*, *16x*, *14y*, winding of relay *Z*, battery, earth. It should be mentioned that relay *Z* energizes before relay *D*. Thus relay *A* still remains energized. Through the energizing of relay *Z* the following circuit is again completed over winding *I* of transformer *Tr*: earth, contacts *6z*, *5a*, winding of transformer *Tr*, battery, earth. In the transformer *Tr* another induction impulse is induced in the positive direction which affects the polarized receiving relay 20 *P* in the repeater *Ue2* so that contact *51p* is opened and contact *50p* is closed. Relay *J* in the repeater *Ue2* thus continues to remain energized so as to insure the energizing of relay *G* and consequently the completion of the seizing. 25

30 In repeater *Ue1* relay *Z* locks up in the following circuit: earth, contacts *15x*, *13e*, *16x*, *17z*, winding of relay *Z*, battery, earth. Relay *Y* de-energizes after the opening of contact *18z*. In the meantime the slow energizing relay *D* also energizes through contact *22e*. Relay *D* by opening contact *21d* breaks the circuit for relay *A*. Relay *A* releases and breaks the circuit through winding *I* of transformer *Tr* by opening its contact *5a*. Accordingly an impulse is induced in the transformer, this time in the negative direction. This last subsidiary impulse brings the seizing impulse to an end. In the repeater *Ue2* the armature of relay *P* is again switched over by this impulse, contact *50p* opens, and contact 40 *51p* closes. Relay *J* releases and by closing contact *58i* causes relay *S* to release. 45

The release is effected as already described by breaking the testing circuit in the pre-arranged selector, whereby relay *C* releases in the repeater *Ue1*. A prolonged induced impulse is transmitted over the connecting line *VL* in a positive direction, and the negative induced impulse is suppressed. The release in repeater *Ue2* takes place as already described. The switching processes for the release are not fundamental to the invention and are therefore not shown. 55

Having described the invention, what is considered to be new and is desired to be protected by Letters Patent will be set forth in the following 60 claims.

What is claimed is:

1. In a telephone system, a trunk line having two branches, means for producing induced current impulses in said trunk line, switching means in said trunk line, means responsive to the transmission of a seizing induced impulse in said trunk line for operating said switching means to connect with one of the branches of the trunk line, and means responsive to the interruption of the seizing impulse for connecting with the other one of said branches. 65
2. In a telephone system, a trunk line having its outgoing end extending in two different traffic directions and in which induced current impulses are produced for seizing and setting the 70
- 75

automatic switches in which the traffic directions terminate, switching means in said trunk line for determining which of said traffic directions is to be utilized, means for transmitting an induced impulse to seize said trunk line and operate said switching means to connect said trunk line with one of said traffic directions, and means for interrupting said seizing impulse to operate said switching mechanism to connect the trunk line with the other of said traffic directions. 10

3. In a telephone system, a trunk line branched at its outgoing end into two different traffic directions, switching means in said trunk line for determining which of said branches is to be used, means for transmitting induced impulses over 15 said trunk line, said switching means operative responsive to a seizing induced impulse to connect said trunk line with one of its outgoing branches and responsive to the interruption of the seizing impulse for connecting the trunk line with the other of said branches. 20

4. In a telephone system, a trunk line branched at its outgoing end and normally connected to one of the branches, switching means in said trunk line for producing induced impulses, automatic means for seizing said trunk line in one manner and operating said switching means to produce an induced impulse and maintain the connection of the trunk line with the normally connected branch, and automatic means for seizing said trunk line in another manner and operating said switching means to produce a different induced impulse to switch the connection of the trunk line from the normal to the other branch. 25

5. In a telephone system, a trunk line having two branches, means for seizing said trunk line, switching means in said trunk line operative responsive to the seizing of the line for extending the trunk line over one of its branches, other 40 switching means in said trunk line operative responsive to the seizure of the trunk line for interrupting said seizing means to extend the trunk line over the other of its branches, said seizing means comprising induced positive and negative 45 impulses.

6. In a telephone system, a trunk line having two branches, means for seizing said trunk line over two different paths, the path over which said trunk is seized determining the branch which is 50 to be used, means in the outgoing end of the said trunk line for transmitting induced impulses thereover, means in the incoming end of the trunk line responsive to the receipt of an induced impulse and depending upon over which path the 55 trunk line is received for extending the trunk line over one of its branches in the incoming end of the trunk line if the trunk is seized over the other path for interrupting the induced impulse to extend the trunk line over the other of its branches. 60

7. In a telephone system as claimed in claim 6, in which the induced impulses comprise positive and negative impulses and in which the impulse transmitting means after interrupting the induced impulse transmits a negative impulse for 65 terminating the seizing of the trunk line.

8. In a telephone system, a trunk line having two branches, means for seizing said trunk line over two separate paths, the path over which the trunk line is seized determining the branch over 70 which it is extended, means in the outgoing end of said trunk line for transmitting induced positive and negative impulses thereover, the seizing of the trunk line over one path being effective to transmit an induced impulse to the incoming 75

- end of said trunk line, and means at said incoming end of the trunk line responsive to said induced impulse for selecting the corresponding trunk line branch.
5. In a telephone system as claimed in claim 8, wherein responsive to the induced positive and a negative impulse transmitted over the incoming end of the trunk line to select the required branch, relay means are operated in one manner, while 10 the relay means are operated in another manner in case there is a pause between the positive and negative impulse.
10. In a telephone system, a trunk line having two branches, means whereby said trunk line 15 is seized over two different paths, the path over which said trunk is seized determining the branch which is to be used, means in the outgoing end of said trunk line for transmitting induced impulses thereover responsive to the seizure of said trunk line over either of the paths, means responsive to said induced impulse for selecting one 20 of the branches and responsive to an interruption of the induced impulses for selecting the other branch, automatic switches connected to each of said branches, said switches prepared for operation responsive to the selection of the associated branch and independent of the induced impulse 5 transmitted for selecting the branch.
11. In a telephone system, a trunk line having two branches and an automatic switch in each branch, means for seizing said trunk line over two separate paths, the path over which said 10 trunk line is seized determining the branch which is to be used, means in the outgoing end of said trunk line responsive to its seizure over either path for transmitting induced impulses thereover, a polarized relay in the incoming end of the trunk 15 line responsive to the induced impulses transmitted over the trunk line, and means controlled by said polarized relay and depending upon the character of said induced impulses for selecting the desired branch and preparing the automatic 20 switches thereon for operation.

RUDOLF PFANNSCHMIDT.
